UNITED STATES PATENT OFFICE.

OTTO GELHAAR, OF MILWAUKEE, WISCONSIN, ASSIGNOR TO NATIONAL BUILDING BLOCK COMPANY, OF MILWAUKEE, WISCONSIN, A CORPORATION OF WISCONSIN.

BUILDING-BLOCK AND WALL.

SPECIFICATION forming part of Letters Patent No. 773,493, dated October 25, 1904.

Application filed April 18, 1904. Serial No. 203,569. (No model.)

To all whom it may concern:

Be it known that I, OTTO GELHAAR, a citizen of the United States, residing at Milwaukee, in the county of Milwaukee and State of Wisconsin, have invented certain new and useful Improvements in Building-Blocks and Walls, of which the following is a specification, reference being had to the accompanying drawings, forming a part thereof.

- 10 This invention relates to building-blocks made of concrete or similar material and to walls constructed of such blocks. Its main object is to provide blocks of a shape which can be easily molded to resemble any desired material—such as brick, smooth or rough stone, and the like—and readily laid in regular courses to form substantial walls with symmetrically-broken joints and internal air-spaces.
- 15 It consists in certain novel features of construction and in the peculiar arrangement of the blocks to form walls, as hereinafter particularly described, and pointed out in the claims.
- 20 In the accompanying drawings like letters designate the same parts in the several figures.

Figure 1 is a horizontal section of a course of blocks constructed and arranged according to my invention. Fig. 2 is a plan view of a course in which the blocks are arranged to break joints at the ends with the blocks as arranged in Fig. 1; and Fig. 3 is a perspective view of a piece of wall in which a corner is turned, illustrating the arrangement of the blocks as they are laid in a number of horizontal courses one upon another.

The blocks *aa* of which an ordinary straight wall is mainly constructed are each formed at one end with a transverse projection *b* and at 40 the other end with an inwardly-extended transverse abutment or bearing-face *c* and between the ends with an inwardly-projecting longitudinal abutment or bearing-face *d*, extending vertically across and parallel with the inner 45 face of the block. The inside corners of the blocks are preferably rounded, as shown.

The projections *b*, which are formed substantially at right angles to the body of the

blocks, are approximately equal in length to the thickness of the wall for which they are 50 designed, less the thickness of the blocks through the abutments *d*, which are located about midway between the ends of the blocks.

In the construction of a wall with these blocks they are laid in horizontal courses, one 55 course upon another, so as to regularly break joints at the ends, as shown in Fig. 3. In each course the inside blocks are reversed with relation to the outside blocks, so that the end projections *b* of the blocks on each 60 side of the wall will extend across the intermediate space to the opposite abutments *d* of the blocks on the other side of the wall, and the vertical end joints on one side will consequently alternate with those on the other 65 side of the wall. To turn or form a corner, two slightly-modified forms of blocks *a'* and *a''* are provided. The outer block *a'* is like the standard block, except that its right-angled end projection *b'* is made somewhat longer 70 than the projection *b* of the standard block and is located at a distance from its intermediate abutment *d* corresponding to the thickness of the wall, thus making the block somewhat 75 shorter than the standard block. The inner block *a''* is like the standard block, except that the end opposite its projection *b* is shorter, its length from its intermediate abutment *d* being such that it will when arranged as shown in the drawings terminate against or 80 close to the abutment *d* of the associated outer corner-block *a'*. In successive courses the arrangement of these corner-blocks *a'* and *a''* is reversed, as shown in Figs. 1 and 2, so 85 that the projection *b'* will alternate with the bodies of the blocks, and the joints between the ends of the blocks in each course will alternate with the joints between the ends of the blocks in the adjoining course or courses, as shown in Fig. 3. The blocks are all bound 90 together by cement or mortar applied to their adjoining faces, as indicated in the several figures, by the narrow spaces between the blocks.

It will be observed that by the reversed arrangement of the blocks in successive courses 95

the end projections *b* of the blocks on each side of the wall in each course are made to overlap the corresponding end projections of the blocks on the other side of the wall in the

5 preceding course, thus binding the inner and outer parts of the wall securely together.

By the arrangement of the blocks as herein shown and described a wall is formed with vertical air spaces or passages *ee*.

10 The blocks may be molded on the outside to imitate brickwork, dressed or rock-faced stone, and the like of any desired color.

15 Various changes in minor details of construction and arrangement may be made to adapt the block to varying conditions and requirements without departing from the principle and intended scope of the invention.

I claim—

20 1. A building-block having a transverse projection at one end only and an inwardly-projecting abutment on its inner face between its ends, and shorter than the length of the end projection, the end projection being approximately equal in length to the thickness 25 of the wall for which designed less the thickness of the block through said abutment, substantially as described.

25 2. A building-block having an inwardly-extending projection at one end only, an inwardly-extended transverse bearing-face at the opposite end and an inwardly-projecting abutment between the ends, shorter than the length of the end projection, the end projection being approximately equal in length to 35 the thickness of the wall for which designed less the thickness of the block through said abutment, substantially as described.

30 3. A building-block having a transverse projection at one end and an inwardly-projecting abutment on its inner face between its ends, the transverse end projection being located at a distance from said abutment corresponding approximately to the thickness of the wall for which it is designed, substantially as de- 35 scribed.

35 4. A building-block having a transverse projection at one end and an inwardly-projecting abutment on its inner face between its ends, the distance between said abutment and the 40 end of the block opposite the transverse projection being less than the distance between said abutment and the transverse projection and such that when positioned in a wall, at its

corner, the short end of the block will terminate at the intermediate abutment of an associated outer corner-block, substantially as described.

5. A wall composed of blocks, each having a transverse projection at one end only and an inwardly-projecting abutment between the ends on one side, laid in courses with the blocks on the inner and outer sides of each course reversed and breaking joints at the ends and inclosing intermediate spaces, the transverse end projections of the blocks on each side of the wall being approximately equal in length to the thickness of the wall less the thickness of the blocks through said abutments and bearing against the intermediate abutments of the blocks on the opposite side of the wall, and the end joints in each course alternating with the end joints in the adjoining course, substantially as described.

6. A wall composed of blocks, each having a transverse projection at one end only and an inwardly-projecting abutment between the ends on one side, laid in courses with the blocks on the inner and outer sides of each course reversed and breaking joints at the ends and inclosing intermediate spaces, the transverse projections of the blocks on each side of the wall being approximately equal in length to the thickness of the wall less the thickness of the blocks through said abutments and bearing against the intermediate abutments of the blocks on the opposite side of the wall, and the end joints in each course alternating with the end joints in the adjoining course, the outer corner-block of the wall having the transverse end projection spaced from the inwardly-projecting abutment a distance corresponding approximately to the thickness of the wall, and the inner corner-block having its end next to its abutment at a distance from the abutment less than the distance between the abutment and the transverse end projection and such that the short end of the block will terminate at the intermediate abutment of the associated outer corner-block in the wall, substantially as described.

In witness whereof I hereto affix my signature in presence of two witnesses.

OTTO GELHAAR.
